US00D878606S

(12) **United States Design Patent** (10) Patent No.: **US D878,606 S**
(45) Date of Patent: ** *Mar. 17, 2020

(54) **FLUID REMOVER**

(75) Inventors: **Patrick J. Minnelli**, Harrison, OH
(US); **Kevin M. Montgomery**,
Camden, OH (US)

(73) Assignee: **Ethicon LLC**

(*) Notice: This patent is subject to a terminal disclaimer.

(**) Term: **14 Years**

(21) Appl. No.: **29/403,077**

(22) Filed: **Sep. 30, 2011**

Related U.S. Application Data

(63) Continuation of application No. 12/902,265, filed on Oct. 12, 2010, now Pat. No. 8,636,686, which is a continuation-in-part of application No. 12/533,590, filed on Jul. 31, 2009, now Pat. No. 8,568,362, which is a continuation-in-part of application No. 12/110,724, filed on Apr. 28, 2008, now Pat. No. 8,579,807, and a continuation-in-part of application No. 12/110,727, filed on Apr. 28, 2008, now Pat. No. 8,870,747, and a continuation-in-part of application No. 12/110,742, filed on Apr. 28, 2008, now Pat. No. 9,358,041, and a continuation-in-part of application No. 12/110,755, filed on Apr. 28, 2008, now Pat. No. 8,273,060.

(57) **CLAIM**

The ornamental design for a fluid remover, as shown and described.

DESCRIPTION

FIG. 1 is a perspective view of a fluid remover for use with a trocar;

FIG. 2 is a top view of the fluid remover of FIG. 1;
FIG. 3 is a back side view of fluid remover of FIG. 1; and,
FIG. 4 is a front side view of the fluid remover of FIG. 1.

1 Claim, 1 Drawing Sheet
